Inventor

JOHN MONTGOMERY.

By *Edgarmond A. Parker*

Attorney

UNITED STATES PATENT OFFICE.

JOHN MONTGOMERY, OF TORONTO, ONTARIO, CANADA.

CAR DOOR.

Application filed August 14, 1920. Serial No. 403,539.

To all whom it may concern:

Be it known that I, JOHN MONTGOMERY, a subject of the King of Great Britain, residing at Toronto, county of York, Province of Ontario, Canada, have invented a certain new and useful Improvement in Car Doors, and declare the following to be a full, clear, and exact description of the same, such as will enable others skilled in the art to which it pertains to make and use the same, reference being had to the accompanying drawings, which form a part of this specification.

My invention relates to car doors and one object of my improvements is to provide a combined door that shall facilitate the various operations of loading and unloading the car. The various closures may be sealed with a single seal.

20 In the accompanying drawings,—

Figure 1 is an elevation of an apparatus embodying my invention and as much of the side of a car as is necessary to illustrate its connection therewith.

25 Fig. 2 is an elevation to a larger scale showing the lower right-hand corner of the door with the adjacent operating mechanism.

Fig. 2^A is a detail section on the line 30 III^A—III^A of Fig. 2.

Fig. 3 is a view in elevation showing the upper right-hand corner of the apparatus of Fig. 1 to a larger scale.

Fig. 4 is a section on the line IV—IV, 35 Fig. 3.

Fig. 5 is a section on the line V—V, Fig. 4.

Fig. 6 is a section approximately in a plane indicated by the line VI—VI, Fig. 2^A.

40 Fig. 7 is a detail plan view showing the left-hand portion of the door track g.

Fig. 8 is a detail section on the line VIII—VIII, Fig. 1.

Fig. 9 is a sectional plan view on the line 45 IX—IX, Fig. 1.

Fig. 10 is a view to an enlarged scale of the parts shown to the right of Fig. 9.

I have shown my invention combined with the apparatus shown in patent granted to me May 7, 1918 and numbered 1,265,478.

a indicates the side of the car and a² the car door as a whole which slides upon the track g. b, b and b² are the movable strips

shown in my patent referred to. c is an actuating bar for the strips b, b and b². 55 d is a bell-crank lever pivoted at d² to the side of the car near the door and having its shorter arm connected by a pivoted link to the operating bar c. d¹ is a handle upon the bar d. d³ is a latch pivoted to the lever d and adapted to engage through a staple or securing eye d⁶ fixed to the side a of the car. d⁵ is the hook upon the latch d³ which is adapted to be engaged through the securing eye d⁶ and then have the car 65 seal attached to it to lock the lever in the position shown in Fig. 1.

e is an upright bar pivoted in bearings e², e^{2a} adjacent and parallel to the right-hand edge of the door a², as shown in Fig. 70 1. e³ and e⁶ are ferrules or sleeves upon the bar e secured in place by set screws. e⁷ and e⁸ are engaging hooks extending from the sleeves e³ and e⁶.

j is a sliding door adapted to reciprocate 75 in grooves or tracks j⁷, j⁷ upon the door a² to open and close a portal through the door a². j² is a bell-crank lever pivoted at j³ to the door j. j⁴ is a vertical, downwardly-extending short arm of the bell-crank lever 80 j². j⁵ is a pawl pivoted at one end to the arm j⁴ of the bell-crank lever j². j⁶ indicates a series of equally-spaced teeth adjacent to the line of travel of the lower end of the lever arm j⁴ extending parallel to the line of travel of said arm and fixed to the door a². The pawl j⁵ is adapted to engage the teeth j⁶ and it may turn about the pivot j⁴ to one side or the other of said arm, as indicated in dotted lines in Fig. 1. j⁸ is 85 a lug extending from the right-hand end of the door j and having an aperture in its outer end. The hook e⁸ is adapted to engage through the aperture in the lug j⁸ to secure the door j in its closed position.

k is a door adapted to open and close a portal in the upper portion of the door a² and to slide horizontally in grooves or tracks k², k². k³ is a lug similar to the lug j⁸ but extending from the door k. The hook e⁷ 100 is adapted to engage in the aperture in the outer end of the lug j⁸ to secure the door k in its closed position.

e¹³ is a lever arm fixed to the rod e and adapted to be manipulated to rotate said rod 105 whereby the hooks e⁷ and e⁸ may be engaged

with their respective lugs b^3 and j^8 or may be turned to disengage them from said lugs. b^8 is an engaging lug on the movable strip b adapted to pass over the lever arm e^{13} and secure said arm from rotation in the position in which the hooks e^7 and e^8 are engaged with their respective lugs.

g indicates the track or way upon which the door a^2 engages by means of hangers e^4 , e^5 having the usual friction rollers. The track g is a metal trough, the cross-section of which is shown most distinctly in Fig. 4. Its web extends over the upper edge of the door a^2 and deflects any rain or other loose material so that it shall not enter a car between the upper edge of the door and the car body. g^2 indicates apertures, a series of which are formed along the outer edge of the lower wall of the track g . The hanger e^4 engages by a grooved wheel h (Fig. 4) the upturned outer edge of the track g . The hanger e^4 is formed in a loop in its lower end having horizontal portions e^{4a} and e^{4b} . e^9 is an eccentric cylinder fixed to the upper end of the rod e and engaging through apertures in the horizontal portions e^{4a} , e^{4b} of the loop of the hanger e^4 . By this arrangement, when the rod e is turned to the position to engage doors j and k , the eccentric e^9 acts upon the hanger e^4 to press the upper edge of the door at its right-hand portion close against the side of the car bordering the door-way. The other edge of the upper portion of the door is forced into close engagement with the car by the outer flange of the track g which converges inward, as shown in Fig. 7, so as to bring the left-hand edge of the door into close engagement with the car wall when the door is closed.

e^{10} is a cylindrical sleeve fixed at the lower end of the bar e and having an outwardly projecting lug e^{11} (Fig. 6) thereon. e^{12} is a lug or dog rotatably sleeved upon the rod e just below the sleeve e^{10} and so located that it may engage a part f fixed to a strip b^2 and extending upward therefrom. e^{12a} and e^{12b} are shoulders upon the lug e^{12} interposed in the line of travel of the lug e^{11} so as to allow a considerable free movement of said lug before it engages said shoulders. When the rod e is turned to its engaging position the lug e^{11} has engaged the shoulder e^{12a} rotating the lug or dog e^{12} until it engages the vertically-extending portion of the part f and has pressed the door a^2 firmly against the side of the car, thus making a tight, closed engagement.

The door may have any side or end clearance thought desirable. When the door is fully released, the bottom of the door swings outward from the car and comes to rest against brackets or parts f , f . These parts f are securely fastened to the sliding plate b^2 and at all positions project above said sliding plate half an inch, and the lower

edge or the bottom of the door catches against these brackets or parts f , f and holds the door from further outward movement.

This outward movement is useful at large grain elevators, as it permits the grain that is pressing against the inside of the door to slide at once into the elevator hopper.

The operation of the above-described device is as follows:

When the car is loaded and the door closed, it may be desirable to take out a portion of the load which may be of grain or similar material. In such case the lever arm e^{13} is loosened by withdrawing the lugs b^3 therefrom; said lever arm is then turned, rotating the rod e to disengage the hooks e^7 , e^8 from their respective lugs. The pawl j^5 being in the position shown in Fig. 1, the bell-crank lever j^2 is oscillated, which on its downward motion acts upon one of the teeth j^6 through the pawl j^5 to move the door j a short distance toward its open position. The bell-crank lever is then moved until the pawl j^5 engages the next of the teeth j^6 and the operation is repeated until the door j is opened to the extent desired. When it is desired to close the door j the pawl j^5 is turned over as indicated in dotted lines, and the same operation of the bell-crank lever j^2 now acts to forcibly close the door.

If it is desired to enter the car for any reason, while partly loaded, the door k at the upper portion of the door a^2 may be moved along the tracks or grooves k^2 , k^2 to open the portal. When the doors j and k have been closed the bell-crank lever d is moved to the position shown in Fig. 1, forcing the bar b at the right of the door a^2 upward to engage the lug b^3 over the lever arm e^{13} . In this position the door a^2 is firmly and tightly closed and the doors j and k are closed and locked by the hooks e^7 and e^8 . The latch d^3 is now engaged with the securing eye d^6 and the seal is adjusted, thus securing all three doors by a single seal.

The way in which the right-hand edge of the door a^2 is forced closed against the side of the car by the turning of the rod e by means of the handle e^{13} has been described above in connection with the detailed description of the parts.

The shape of the track g in cross section is such as to carry the water away from the car door and discharge it at some distance from the joint between the door and the car wall.

What I claim is:

1. In an apparatus of the kind described, the combination of an outer door, a portal through said door, an auxiliary door adapted to slide horizontally to more or less cover said portal, a series of stationary teeth on said door extending parallel to the line of motion of said auxiliary door and adjacent to said door, an oscillating lever on said

- door having a vertically-extending arm, a pawl pivoted at the end of said arm adapted to successively engage said teeth to impart sliding motion to said auxiliary door, the relative position of said teeth and lever and the length of said pawl being such that the pawl is held at an angle slanting outwardly and toward said teeth and in engagement with said teeth by the gravity of said pawl.
2. In an apparatus of the kind described, the combination of an outer door, a portal through said door, an auxiliary door adapted to slide horizontally to more or less cover said portal, a series of stationary teeth on said door extending parallel to the line of motion of said auxiliary door and adjacent to said door, an oscillating lever on said door having a vertically-extending arm, a pawl pivoted at the end of said arm adapted to successively engage said teeth to impart sliding motion to said auxiliary door, the relative position of said teeth and lever and the length of said pawl being such that the pawl is held at an angle slanting outwardly and toward said teeth and in engagement with said teeth by the gravity of said pawl, said pawl being adapted to be turned about its pivot to similarly engage said teeth upon the opposite side of said lever.
3. The combination with a freight car having a door-way in its wall, an outside sliding door adapted to close said door-way, an auxiliary door adapted to close a portal in said door, means upon said door adapted to force the same into close engagement with the wall surrounding said door-way, said close engaging means being adapted to lock said auxiliary door in its closed position.
4. The combination of a freight car having a door-way through its wall, a door adapted to engage over said door-way from outside of said wall, an oscillating part on the outer surface of said door, a fixed part on the wall of said car adjacent to the edge of said door, and a dog or engaging lug adapted to be actuated by said oscillating part to engage said fixed part and be pressed against the same in a manner to force said door against the wall of said car, a portal in said door, an auxiliary door adapted to close said portal, said oscillating part being adapted to lock said auxiliary door when turned to engage the main door against its bearing.
5. The combination with a car, a sliding door therefor, an auxiliary door adapted to govern a portal in the main door, an oscillating part on said main door, a handle on said oscillating part, said oscillating part being adapted to engage and lock said auxiliary door and said handle being adapted to engage a part carried by the car to prevent the oscillation of said oscillating part when the auxiliary door is locked, said oscillating part being adapted to force the door toward the car when the auxiliary door is locked.
- In testimony whereof, I sign this specification.

JOHN MONTGOMERY.
